[57] CLAIM

The ornamental design for a key holder, as shown and described.

DESCRIPTION

FIG. 1 is a top plan view of the key holder of the present invention;

FIG. 2 is a right side elevational view of the key holder of FIG. 1, the left side elevational view being a mirror image thereof;

FIG. 3 is a bottom plan view of the key holder of FIG. 1; FIG. 4 is a front elevational view of the key holder of FIG. 1;

FIG. 5 is a rear elevational view of the key holder of FIG. 1; and,

FIG. 6 is a perspective view of the key holder of FIG. 1, shown on the wrist of a wearer in use.
